PRESSURE ADJUSTMENT AND TRIP FOR
PRINTING CYLINDERS

Henri E. Peyrebrune, River Forest, Ill., assignor,
by mesne assignments, to Miehle Printing Press
& Manufacturing Company, Chicago, Ill., a cor-
poration of Delaware

Application March 22, 1946, Serial No. 656,255

4 Claims. (Cl. 101—218)

1

The invention relates to printing presses and has reference more particularly to improved tripping mechanism for an offset printing press incorporating a novel arrangement of adjustable eccentrics for effecting a tripping operation of the blanket cylinder with respect to the impression and plate cylinders, respectively, with means being provided in combination with said eccentrics for adjusting the squeeze pressure on sheets passing between the blanket and impression cylinders during the printing operation.

In offset printing presses the impression to be printed is transferred by the plate cylinder to the blanket cylinder which in turn forms a printing couple with the impression cylinder to print the design on sheets passed between the cylinders. It is old in the art to trip the cylinders of such a press to interrupt the regular contact between the cylinders thereby to intermittent the normal printing operation. For such tripping purposes it has been proposed to eccentrically mount the impression cylinder and to also eccentrically mount the blanket cylinder, independent actuation of said eccentrics serving to produce the desired tripping functions. Subsequent developments, as disclosed by the patent to Robertson 1,107,843, granted August 18, 1914, contemplate the mounting of the blanket cylinder for movement in two directions with tripping of said cylinder from the plate and then from the impression cylinder taking place in timed sequence and in the order named. More recent improvements as disclosed in the patent to Hunting 2,356,058, granted August 15, 1944 reside in the provision of trip mechanism for the blanket cylinder, initiated by the absence or misalignment of a fed sheet, for automatically tripping the blanket cylinder from the plate cylinder, said action setting the mechanism for tripping the blanket cylinder from the impression cylinder, the tripping action in each case taking place while the gaps of adjacent cylinders are passing.

According, an object of the present invention resides in the provision of tripping mechanism embodying improvements in construction and mode of operation over previously known mechanism representing the prior art.

A further object of the invention resides in the provision of improved tripping mechanism for offset presses embodying a novel arrangement of eccentrics for journalling the blanket cylinder and which will have a mode of operation whereby both eccentrics are instrumental in effecting movement of the cylinder for tripping

2

with respect to the impression and also the plate cylinder, although rotation is imparted to only one eccentric at a time for producing the tripping operations, respectively.

5 Another object is to provide improved tripping means for an offset press having eccentric mechanism at the respective ends of the blanket cylinder for journalling the cylinder, providing for movement in two directions whereby to move the blanket cylinder out of contact with the impression and plate cylinders respectively, and wherein said mechanism embodies two eccentrics having mounting relation one on the other with relative rotation of the eccentrics taking place

15 for effecting said tripping operations.

Another object of the invention is to provide eccentric journalling mechanism for the respective ends of the blanket cylinder adapted to effect tripping movements of said cylinder with 20 respect to the impression and plate cylinders and wherein said eccentric journalling mechanism has combined therewith pressure adjusting means for varying the squeeze pressure on the sheets as they pass between the impression and blanket cylinders during the printing operations.

Another object of the invention is to provide eccentric journalling mechanism of the type and for the purposes described having combined therewith pressure adjusting means for varying 30 the printing pressure between the blanket and impression cylinders and which is capable of actuation to adjust said pressure during a printing operation, the said pressure adjusting means incorporating a combination worm and spur gear and associated mechanism making possible said adjustments during printing.

With these and various other objects in view, the invention may consist of certain novel features of construction and operation, as will be 40 more fully described and particularly pointed out in the specification, drawings and claims appended hereto.

In the drawings which illustrate an embodiment of the device and wherein like reference characters are used to designate like parts—

Figure 1 is a vertical sectional view showing the trip mechanism of the invention applied to the blanket cylinder of an offset printing press, the cylinders being on impression;

Figure 2 is a vertical sectional view similar to Figure 1 but showing the trip mechanism in tripped position with the cylinders off impression;

Figure 3 is a transverse sectional view taken

vertically through the frame of the press and showing the eccentric journaling members comprising the trip mechanism of the invention;

Figure 4 is an elevational view showing the improved gear drive for the pressure adjusting means of the invention; and

Figure 5 is a sectional view taken substantially along line 5—5 of Figure 1.

Referring to the drawings, particularly Figures 1, 2 and 3, the side frames 10 comprise the side members of a conventional offset type of printing press which has been selected for illustrating the present invention. The side frames are spaced for receiving and journaling the printing instrumentalities including a plate cylinder 11, a blanket cylinder 12, and an impression cylinder 13. The plate cylinder 11 carries the conventional plate which is inked by inking rollers not shown since they form no part of the present invention. The inked impression from cylinder 11 is transferred to the rubber blanket or the like on cylinder 12 and said cylinder and the impression cylinder 13 form a printing couple with the inked impression on the blanket cylinder being applied to sheets of paper passed between said cylinders, one impression taking place for each revolution thereof. As is well understood in the art, it is desirous at times to move the blanket cylinder 12 out of engagement with the plate and impression cylinders, as for example, for preliminary inking of the plate cylinder, or when it is found that a sheet is not being fed to the printing couple or is being fed improperly registered. The movement of the blanket cylinder from contact with its companion cylinders will enable the passing of a sheet through the press without giving the sheet an impression.

For tripping the blanket cylinder as above described, the cylinder is journalled at its respective ends by a novel arrangement of eccentrics, as best shown in Figures 1 and 2. However, the plate cylinder 11 is journalled in the frames of the press by means of fixed bearings and the impression cylinder 13 is likewise journalled in fixed bearings whereby these cylinders do not have bodily movement but only rotary movement for performing the printing operations. The journaling shaft 14 for the blanket cylinder 12 is mounted at its respective ends by an inner eccentric journaling member 15, as illustrated by Figure 3, the said member providing the roller bearings 16. The outer eccentric journaling member 17 is mounted on member 15 in a manner whereby the same may rotate with respect to member 15. The journaling member 17 is supported by the frame 10 of the press and conventional mechanism is provided, to be presently described, for independently rotating the eccentric members 15 and 17 to effect the tripping movements of the blanket cylinder.

The arrangement of the three cylinders is such that the period of time, during which the inked plate is transferring the design to the blanket cylinder 12, is not coincident with the period of time during which the impression is being printed upon the paper passing between the cylinders 12 and 13. Thus, it is desirable, in the event of a misfeeding or misalignment of a fed sheet, to first trip the blanket cylinder with respect to the impression cylinder, and then with respect to the plate cylinder, thus permitting the complete transfer of the inked impression from the plate cylinder to the blanket cylinder. By completing the transfer of the impression to the blanket cylinder proper printing of the first sheet

takes place following the tripping operation. In other words, since the two operations of inking and printing are sequential, the trip and return of each should be sequential, and this mode of operation is contemplated for the two eccentric journaling members, namely, 15 and 17, provided by the present invention for journaling the respective ends of the blanket cylinder.

Referring to Figure 1, which shows the cylinders on impression, it will be observed that the eccentric 15 has been located in a definite position with respect to the axis a—b which connects the centers of cylinders 11 and 12. The high portion 18 of said eccentric and the low portion 20 of the same are in opposed relation and are approximately bisected equally by said axis. Referring to the eccentric journaling member 17, it will be observed that a similar arrangement also exists. The axis c—d connects the centers of cylinders 12 and 13 and the eccentric 17 has a definite relation with respect thereto and wherein said axis bisects approximately equally the high portion 21 and the low portion 22 of said member. As a result of this construction rotation of the inner eccentric 15 will operate to move the blanket cylinder in a direction substantially parallel to axis c—d, thereby tripping the blanket cylinder 12 with respect to impression cylinder 13. Rotation of the outer eccentric 17 will move cylinder 12 in a direction substantially parallel to the axis a—b and consequently effects tripping of the blanket cylinder 12 from the plate cylinder 11. Rotation of said eccentrics for tripping purposes is accomplished automatically during operation of the press and the invention contemplates the provision of any conventional mechanism for this purpose whereby rotation in clockwise direction is applied to the shaft 23 for tripping with respect to the impression cylinder, and then to shaft 24, for tripping with respect to the plate cylinder.

Upon rotation of shaft 23 motion is imparted to yoke 25 since the parts are connected by means of the lever 26 and link 27. The link is pivoted to the lever at 28 and the opposite end of the link is pivoted at 30 to an ear 31 formed integral with and projecting outwardly of yoke 25. Said shaft 24 has the lever 32 fixed thereto and the end of this lever is pivotally connected as at 33 to the threaded member 34. The member passes through sleeve 36 and is suitably held to the sleeve in adjusted position by means of the nuts 37 at the respective ends of the sleeve. The sleeve is pivotally joined as at 38 to the bracket 40 suitably secured as by screws 41 to the outer eccentric 17. The yoke 25, as best shown in Figure 3, is rotatably mounted on the inner eccentric 15 having a juxtaposed position, however, with respect to the outer eccentric 17. The worm wheel gear segment 42 is suitably secured to eccentric 15 as by means of the bolts 43 and the parts are locked in secured relation by means of the key 44. Adjustable connection between the eccentric 15 and the yoke 25 is accomplished through the instrumentality of the combination worm and spur gear 45 carried by the yoke, the said gear being located between the outwardly projecting bosses 46 and being journalled by the shaft 47. It will be seen that rotation of the combination gear 45 will produce movement of the gear segment 42 and therewith the inner eccentric 15, the spiral convolutions of said gear having meshing relation with the segment. The structure, therefore, provides adjusting means whereby the rotative position of eccentric 15 may

be adjusted relative to the yoke 25. In accordance with the invention it is desirable to adjust eccentric 15 from the exterior of the press frame since the rotative adjustments of this eccentric with respect to its associated parts will vary the squeeze pressure applied to the sheets as they pass between the blanket and impression cylinders in the printing operation. To accommodate rotation of yoke 25 which produces bodily movement of the combination gear 45, the said gear functions both as a worm gear as well as a spur gear, it being clear from Figure 4 that conventional gear teeth are cut into the convolutions forming the worm.

The drive shaft for the printing pressure adjustment is indicated by numeral 50, the same extending transversely of the press, as shown in Figure 4, being suitably journaled at respective ends in the spaced side frames 10. A worm gear 51 is fixed to said shaft 50 at each end of the same relatively adjacent the journaled ends of the shaft and said worm gears have meshing relation with a combination worm and spur gear 45, respectively. This relationship between each worm gear 51 and its respective combination gear 45 is maintained notwithstanding the fact that the combination gear has bodily movement which results from rotation of the yoke for tripping the blanket cylinder with respect to the impression cylinder. It will be observed that when the cylinders are on impression, as shown in Figure 1, the worm 51 has meshing relation with the combination gear 45 adjacent the lower end of said gear. However, when the cylinders are off impression the said worm 51 has meshing relation with the upper end of the combination gear 45. The provision of conventional gear teeth in the convolutions of gear 45 permit this bodily movement when the combination gear rotates upon rotation of worm 51. A sprocket 52 is fixed to the outer projecting end of shaft 50, as shown in Figure 4, and the endless chain 53 operatively connects said sprocket with sprocket 54 journaled by the stud shaft 55 provided by one of the frames 10 of the press. The gear 56 rotating with sprocket 54 has meshing relation with the pinion 57 which pinion is manually rotated by the handle 58. The pinion 60 also has meshing relation with gear 56 and the gear 61 meshes with the pinion so as to be driven thereby. Said gear is suitably fixed to shaft 62 so that the pointer 63 is accordingly rotated upon movement of the gear. The disc 64 is provided with indicia such as 65 indicative of the printing pressure since the graduations on said dial represent the distance between the outer peripheries of the blanket and impression cylinders in units of one-thousandths of an inch.

For describing the operation of the tripping mechanism and pressure adjusting means of the invention, it will be assumed that the cylinders are on impression as shown in Figure 1. In the event it is necessary to trip the blanket cylinder with respect to the impression cylinder, due to the absence of a sheet or the misalignment of a fed sheet, the shaft 23 is automatically actuated by the tripping mechanism of the press, the same rotating in a clockwise direction to impart clockwise rotation to yoke 25 and the inner eccentric 15. The rotation thus imparted to eccentric 15 will produce movement of the cylinder in a direction substantially parallel to the axis c—d, thus spacing the blanket cylinder with respect to the impression cylinder. As a result of this tripping operation the combination gear 45 is

bodily moved, thus changing its position with respect to its driving instrumentality, the worm gear 51. Bodily movement is permitted as a result of the teeth cut in the convolutions of gear 45. Rotation of shaft 23 to trip the blanket cylinder from the impression cylinder will set mechanism which subsequently causes clockwise rotation of shaft 24 and through lever 32 and link 34 the outer eccentric 17 is rotated in a clockwise direction, producing movement of the blanket cylinder in a direction parallel to the axis a—b and thus moving said cylinder out of contact with the plate cylinder 11. As previously explained, since the operations of printing and inking are sequential, the trip and return of each are sequential, and the invention provides a pair of eccentrics at each end of the blanket cylinder capable of such operation and which have associated relation with each other with one eccentric being mounted for rotation on the other.

In accordance with the invention, it is possible to adjust the printing pressure and these adjustments can be made during printing and without disturbing or interfering with the tripping operation. It is only necessary to rotate handle 58 in the required direction for either increasing or decreasing the squeeze pressure, causing rotation of gear 57 and gear 56 meshing therewith. Gear 56 drives the sprocket 54 which in turn drives sprocket 52, causing rotation of shaft 50 and the worm gears 51. This rotation of the worm gears will be imparted to their respective combination gears 45, the same being carried by their yokes 25 and having bodily movement upon rotation of said yokes for tripping purposes. Irrespective of the rotative position of the yokes, however, the gears 45 will be rotated and they will transmit their rotary movement to their respective worm wheel gear segment 42 meshing therewith and thus the inner eccentrics 15 are moved to a corresponding degree. This movement of the inner eccentrics to adjust their rotative position with respect to yokes 25 and the outer eccentrics 17 will vary the spacing of the blanket cylinder with respect to the impression cylinder. Accordingly, means are provided for adjusting the printing, i. e. squeeze pressure exerted by the blanket cylinder on sheets passing through the printing couple and which is operable from the exterior of the press where it is readily accessible to the operator. The extent of the printing pressure is visually indicated by means of pointer 63 associated with dial 64. Rotation of gear 56 produces rotation of pinion 60 and gear 61 with the result that the pointer will move in synchronous relation with the rotation of the combination gears and the pressure adjusting parts associated therewith.

For assembling the eccentrics 15 and 17 it should be understood that eccentric 17 is sectional, being formed of two parts, which construction, however, is not shown since the cross sectional views of the drawings do not permit this disclosure. Conventional means are provided for securing the sections of eccentric 17 together after the same have been properly located on the inner eccentric 15. Another important structural feature is embodied in the design of eccentric 15 which is internally recessed on its respective sides for receiving the preloadable roller bearings 16. These bearings provide substantially frictionless means for journaling the shaft 14 in addition to forming a durable, compact structure which also permits of rotary movement 78 of the eccentric 15 for tripping purposes.

The invention is not to be limited to or by details of construction of the particular embodiment thereof illustrated in the drawings, as various forms of the device will of course be apparent to those skilled in the art without departing from the spirit of the invention or the scope of the claims.

What is claimed is:

1. In a printing press having a plate, blanket and impression cylinder and means for tripping said blanket cylinder away from said plate and impression cylinders, including nested eccentric members, the provision of means for adjusting the position of one of said eccentric members to thereby vary the squeeze pressure of the blanket on the impression cylinder comprising a yoke rotatably mounted on one of said members, a gear segment fixed to said member and arranged to mesh with a driven worm journaled by said yoke and movable bodily therewith, said worm having axial grooves through its spiral convolutions, and manually operable means remote from said cylinder for adjusting the squeeze pressure between said blanket and impression cylinder including a drive worm having meshing relation with the axial grooves of said driven worm, whereby said driven worm may move bodily with said yoke during the tripping operation while maintaining the meshing relation of said gears.
2. In an offset printing press, the combination of a plate cylinder and an impression cylinder having fixed axes of rotation, a blanket cylinder, eccentric means for tripping the blanket cylinder off and on the plate and impression cylinders, and manually actuated adjusting means associated with said eccentric means for varying the squeeze pressure between the blanket and impression cylinders while the press is in operation, said adjusting means including a movable yoke for actuating the eccentric member whereby the blanket cylinder is tripped off and on the impression cylinder, a driving worm mounted for rotation on a stationary shaft, a driven worm carried by said yoke to move bodily therewith, and a worm-wheel gear segment associated with the said member to move it for adjustment of the squeeze pressure, said driven worm having its spiral convolutions cut to provide axially spaced circumferential rows of gear teeth so that the meshing relationship between said worms is maintained irrespective of the position assumed by the driven worm due to its bodily movement.
3. In a printing press, the combination of a plate cylinder and an impression cylinder having fixed axes of rotation, a blanket cylinder operatively associated with said cylinders, a shaft for said blanket cylinder, journaling means at each end of the shaft associated with tripping mechanism for moving the cylinder selectively in two directions, said means each including an inner eccentric member rotatable on the shaft and an outer eccentric member rotatable on said inner member, a yoke mounted on the inner member and rotatable to vary the position of the inner

member with respect to the yoke, adjustable means in the form of a worm journaled by the yoke for bodily movement therewith, said worm having grooves in its spiral convolutions aligned parallel with its axis, a worm segment fixed to the inner eccentric member and arranged to mesh with said worm whereby the squeeze pressure between said blanket cylinder and said impression cylinder may be varied, and means remote from said cylinder and including a drive worm having a constant meshing relation with said driven worm for adjusting said squeeze pressure, said parallel grooves in said driven worm permitting movement of said worm with the yoke while maintaining its meshing relation with the drive worm.

4. In a printing press having a pair of cylinders comprising a printing couple, means for tripping one of said cylinders with respect to the other, including a unitary arrangement of at least one eccentric member at each end of one of said cylinders for journaling the same, said eccentric member being mounted for rotation to perform said tripping operations, means for rotating said member including a yoke rotatably mounted on said member, the provision of means for adjusting the relative positions of said member and said yoke whereby to vary the squeeze pressure between said pair of cylinders and including a gear segment fixed to the eccentric member, a worm journaled in the yoke and arranged to mesh with said segment, said worm being grooved axially to provide spur teeth in its spiral convolutions, a drive worm having a bodily fixed position and arranged to mesh with the spur teeth formed in the first mentioned worm, and means remote from said cylinder and associated with said drive worm for effecting adjustment of said driven worm to thereby vary said squeeze pressure, the grooves in said driven worm permitting constant meshing relation between said worms when the cylinder is tripped as well as when it is in printing position.
